M. M. BOTTEMILLER ET AL

Des. 173,301

OTTOMAN

Filed Sept. 17, 1953

UNITED STATES PATENT OFFICE

173,301

OTTOMAN

Merton M. Bottemiller, Wadena, and Leonard B. Olsen, Minneapolis, Minn., assignors to Homecrest Furniture Company, Wadena, Minn., a corporation of Minnesota

Application September 17, 1953, Serial No. 26,840

Term of patent 3½ years

(Cl. D15—1)

To all whom it may concern:

Be it known, that we, Merton M. Bottemiller and Leonard B. Olsen, both citizens of the United States, residing respectively at Wadena, in the county of Wadena and State of Minnesota, and at Minneapolis, in the county of Hennepin and State of Minnesota, have invented a new, original, and ornamental Design for an Ottoman, of which the following is a specification, reference being made to the accompanying drawing, forming part thereof, and in which

The single figure is a perspective view of an ottoman showing the side, end, and top thereof, embodying our new design.

We claim:

The ornamental design for an ottoman, as shown.
